JACOB LAGOWITZ. OF NEWARK, NEW JERSEY.

Letters Patent No. 77,497, dated May 5, 1868.

IMPROVEMENT IN TRAVELLING-BAGS.

The Schedule referred to in these Letters Patent and making part of the same.

TO ALL WHOM IT MAY CONCERN:

Be it known that I, JACOB LAGOWITZ, of Newark, in the county of Essex, and State of New Jersey, have invented a new and useful Improvement in Travelling-Bags; and I do hereby declare that the following is a full, clear, and exact description thereof, which will enable others skilled in the art to make and use the same, reference being had to the accompanying drawings, forming a part of this specification, in which—

Figure 1 represents a front view of my improved travelling-bag.

Figure 2 is a detail transverse section of the same, taken on the plane of the line $x'x$, fig. 1.

Similar letters of reference indicate corresponding parts.

This invention relates to a new manner of preventing the ends of travelling-bags from getting loose, and consists in attaching, to each of the links by which the ends of the handle are connected with the bag, two arms, which, when the bag is suspended from the handle, fit over and around the sides of the frame, holding the same together, and relieving the lock.

A, in the drawing, represents a satchel, valise, travelling-bag, or carpet-bag, of ordinary or suitable construction. B represents the chain or strap, which is the handle of the bag. The two ends of the chain or handle B are secured to links $\alpha\alpha$, which are, in any suitable manner, hinged to the upper edge or face of the bag-frame.

From the links $\alpha\alpha$ project downward plates or arms $b b$, which, when the bag is suspended from the strap, as in figs. 1 and 2, lap over the sides of the frame, so as to keep the same closed near the ends, to prevent it from opening at the ends, and to relieve the lock.

When the bag is to be opened, the links are turned on their pivots, so as to bring the arms $b b$ in line with or above the upper edge of the frame, as is indicated by red lines in fig. 1.

As soon as the strap is taken hold of, it will at once cause the links to swing up, and the arms, b , to lap over the sides of the bag, to close the same.

A small spring, c, is arranged between the pivoted portion of the link and the top of the frame, to lock the eccentric or flattened lower bar of such link in the open position, so that the device will remain up, and will not spontaneously lock the bag as long as the strap B is undisturbed.

Having thus described my invention, I claim as new, and desire to secure by Letters Patent—

1. An automatic device for closing travelling-bags, consisting of the links or rings $\alpha\alpha$, to which the ends of the chain or strap-handle B are secured, and which carry the arms $b b$ that fit over the sides of the bag, substantially as herein shown and described.

2. The above in combination with the spring c, made as set forth.

JACOB LAGOWITZ.
